UNITED STATES PATENT OFFICE.

FRANK COMTE, OF SPRINGFIELD, NEBRASKA.

DESIGN FOR A SCARF-PIN.

SPECIFICATION forming part of Design No. 22,555, dated June 27, 1893.

Application filed May 10, 1893. Serial No. 473,735. Term of patent 3½ years.

To all whom it may concern:

Be it known that I, FRANK COMTE, residing at Springfield, in the county of Sarpy, in the State of Nebraska, have invented a new and original Design for a Scarf-Pin, of which the following is a full, clear, and exact description, reference being had to the accompanying drawing, forming a part thereof, in which the figure is a face view showing my design.

10 The body A of the device is crescent shape, and terminates at its upper end in a ball like enlargement B, while its lower end is represented as an extension curved downward and terminating in a ball like ornamentation C.

15 A pointed bar like ornamentation extends down from the lower end of the body A as at

D, its upper end extending to the upper ball and ornamented by a representation of transverse corrugations as at D'.

The body A is ornamented by a panel like 20 representation E in which a panel representation F appears which is divided into spaces f. The top of such panel F is ornamented by the representation of a helmet.

I claim—

25 The design for a scarf pin herein shown and described.

FRANK COMTE.
